UNITED STATES PATENT OFFICE.

WARREN C. McCRAY, OF CISSNA PARK, ILLINOIS.

DESIGN FOR AN AUTOMOBILE-BODY.

48,945.

Specification for Design.

Patented Apr. 25, 1916.

Application filed January 21, 1916. Serial No. 73,471. Term of patent 7 years.

To all whom it may concern:

Be it known that I, WARREN C. McCRAY, a citizen of the United States, residing at Cissna Park, in the county of Iroquois and State of Illinois, have invented a new, original, and ornamental Design for an Automobile-Body, of which the following is a specification, reference being had to the accompanying drawing, forming a part thereof.

Figure 1 is a side view; and Fig. 2 is a

top plan view of an automobile body, showing my new design.

I claim:

The ornamental design for an automobile body, as shown.

WARREN C. McCRAY.
